UNITED STATES PATENT OFFICE.

MATTHEW CLARKE, OF WILKES-BARRE, PENNSYLVANIA.

SQUARE.

1,103,564.

Specification of Letters Patent. Patented July 14, 1914.

Application filed May 13, 1913. Serial No. 767,386.

To all whom it may concern:

Be it known that I, MATTHEW CLARKE, citizen of the United States, residing at Wilkes-Barre, in the county of Luzerne and State of Pennsylvania, have invented certain new and useful Improvements in Squares, of which the following is a specification.

My invention relates to new and useful improvements in tri-squares and the primary object of my invention is to provide a tri-square including a blade and stock in which the stock is adjustable in length. In accomplishing this I construct a stock in two parts, including a main stock and a supplemental stock, the latter being adjustably mounted upon the free end of the former and movable toward and away from the same to vary the length of the stock as a whole and also detachable from the same to permit the use of the square with an exceptionally short stock, when desired.

A further object of my invention is to provide a tri-square, the stock of which is provided upon its outer face or edge with a pair of adjustable gage arms which may be moved toward or away from said stock face, one of these gage arms being preferably mounted upon the supplemental stock, while the other is mounted upon the main stock in order that the gage arms may be moved toward and away from each other. And a still further object of my invention is to provide the blade of the tri-square with a plurality of longitudinally extending slots providing a consequent plurality of longitudinally extending marking edges, the slots being so proportioned and formed that the marking edges are spaced at a predetermined distance from each other. In this connection one of the marking edges is provided with a plurality of notches equally spaced apart and adapted to seat a pencil point or the point of a scratch-awl to assist in marking out mortises and the like.

With these and other objects in view, my invention will be more fully described, illustrated in the accompanying drawing, and then specifically pointed out in the claims which are attached to and form a part of this application.

In the drawing: Figure 1 is a top plan view of the tri-square, the adjustable gage arms being shown partially extended in dotted lines; Fig. 2 is an end elevation of

the tri-square, looking toward that end of the stock remote from the blade and showing one of the adjustable gage arms in extended position; Fig. 3 is a longitudinal sectional view taken through the stock on the line 3-3 of Fig. 1 and looking in the direction of the arrows.

Corresponding and like parts are referred to in the following description and indicated in all the views of the drawing by the same reference characters.

My improved tri-square, a preferred embodiment of which is shown in the drawing, includes a blade 10 fixed at one end to one end of a stock, indicated as a whole by the numeral 11, this stock including a main stock portion 12 and a supplemental stock portion 13. The blade 10, as shown in Fig. 3 of the drawing, has one end inserted in a slot formed in one end of the main stock portion 11 in which position it is secured by rivets or other suitable fastening devices 14, the blade being secured to extend at right angles to the stock as is customary. The stock is preferably formed of wood, while the blade is preferably formed of metal, either steel or brass, as preferred.

The blade may be of any suitable length and width and is provided with a pair of spaced apart longitudinally extending slots 15 and 16. The width of the blade and the width of these slots should be so proportioned that the portions of the blade between the slots will be predetermined fractional parts of an inch. For instance, the blade shown in Fig. 1 is assumed to be a blade two inches wide and the slots are so formed that the inner portion of the blade is one-half of an inch wide, the intermediate portion three-eighths of an inch wide and the outer portion five-eighths of an inch wide. By this construction a plurality of marking edges are provided at predetermined distances from the outer edges of the blade, these edges greatly facilitating the cutting of gains for shelves, window frames and the like as by adding together the widths of certain of the portions of the blade between the slots and the widths of the slots, the user is enabled to mark almost any size gain up to two inches.

The outer blade portion is marked off in inches and fractions thereof as is customary and in addition to that the inner edge of said portion is notched as shown at 17, the points of the notches coinciding in each instance with the divisional lines of the scale. These

notches are of great use in marking out mortises and the like as the inner face of the stock may be positioned against the edge of the board, a pencil point or scratch-awl positioned in the notch at the required distance from the stock and the stock then drawn lengthwise of the board drawing the pencil point or awl along the board and marking the same, the engagement of the marking point in the notch insuring the marking of a line equidistant at all points from the edge of the board.

As previously mentioned, the stock of the tri-square is formed in two parts adjustably connected. In carrying this out, the main stock portion 12 is provided in its upper and lower faces with longitudinally extending channels 18 and the supplemental stock is similarly provided with channels 19 which, when the stock portions are placed in longitudinal alignment with each other, form continuations of the channels 18. Spring arms 20 are secured by screws, rivets or other fastening devices 21 in the channels of the supplemental stock in such a manner as to lie flush with the upper and lower faces of said stock portion. The free ends of these arms extend a considerable distance beyond the inner end of the supplemental stock to seat in the channels of the main stock and being of resilient metal and inclined toward each other slightly they exert a frictional gripping force upon the main stock to adjustably bind the two stock portions together. The free ends of these arms are slightly rounded at their corners as shown at 22 to permit ready entering engagement of said ends in the outer ends of the channels 18 when assembling the parts.

It will of course be apparent that the stock portions may be made in any desired length and that the spring arms and channels may be proportioned to give practically any desired range of adjustment by drawing the supplemental stock portion away from the main stock portion. These arms fit closely in their slots and prevent all swinging movement of one stock portion with respect to the other. At the same time this type of fastening permits the ready disconnecting of the supplemental stock from the main stock and the tri-square may therefore be used in cramped quarters with a stock considerably shorter than usual. To assist in drawing the supplemental stock away from the main stock, the inner edge of the supplemental stock portion at that end adjacent the free end of the main stock portion is cut-away as at 23 to furnish an opening in which the finger of the operator may be inserted.

That end of the main stock in which the blade is mounted and the free end of the supplemental stock are provided with adjustable gage arms movable toward and

away from the outer edge of the stock. Each of these gage arms includes a U-shaped body portion of spring metal 24, the sides of which frictionally engage in transversely formed channels 25 of the stock portions in the same manner in which the arms 20 engage and the bight portion of which seats in a recess 25' formed in the outer face of the stock to lie flush therewith. Each of these U-shaped portions or clamps 24 is provided with a lateral extension 26 which, in each instance, extends toward the adjacent end of the stock terminating in a laterally directed end 27. The outer face of the stock is cut-away to receive the extensions 26 and seat the same flush with the remainder of the outer face of the stock and the ends of the stock are cut-away to receive the ends 27. It will therefore be apparent that when these gage arms are in retracted position, their extensions 26 and ends 27 extend about the outer corners of the stock to protect the wood of the same from splintering during use.

Each of the extensions 26 carries a threaded stud 28 which extends into a socket 29 formed in the stock and the ends of the stock are slotted longitudinally to receive milled adjusting nuts 30 through which these studs are threaded. It will therefore be apparent that by rotating the nuts 30, the gage arms may be moved toward or away from the stock, as desired. The adjustable gage arms form in themselves a great improvement over the tri-squares now in use, particularly when the tri-square is employed in putting on siding about window casings and the like, as the outer face of the stock may be placed against the siding and the gage arms extended to bear against the outer edge of the frame and against the wall of the building. When so positioned, a pencil or scratch-awl may be run along the side of the stock to mark the siding at the exact place at which it should be cut. The tri-square may be employed with equal advantage, by extending but one of these gage arms, in marking baseboards and in cutting cross braces in doors and the like.

In order to insure as rigid an engagement of the blade and stock as possible that portion of the blade extending within the stock is cut-away only as shown in dotted lines in Fig. 1 just sufficiently to permit the positioning of the adjusting nut and screw of the adjacent gage arm.

From the foregoing description it will be apparent that I have provided a tri-square which is far superior to those now in use for a number of different reasons, among which, are the provision of a slotted blade, of a stock adjustable in length and adjustable gage arms carried by the stock.

It will of course be understood that I do not wish to limit myself to the specific de-

tails of construction illustrated in the drawing and described in the above specification, as these show merely the preferred embodiment of my invention, and all changes in 5 construction, within the scope of the appended claims may be made at any time without in the slightest degree departing from the spirit of my invention.

Having thus described the invention, what 10 is claimed as new is:

1. A tri-square including a blade, a stock provided at its free end with longitudinally extending channels in its upper and lower faces, a supplemental stock adapted to engage 15 end to end with the main stock and provided in its upper and lower faces with channels in alignment with the channels of the main stock, and spring arms secured in the channels of the supplemental stock and 20 seating by their free ends in the channels of the main stock.

2. A tri-square including a blade, a stock, and a supplemental stock removable from the main stock, the main stock having channels 25 formed in opposite faces and the supplemental stock having spring arms extending from its end for frictional engagement in the channel.

3. A tri-square including a stock, and a 30 blade extending at right angles to the stock, said blade being provided with a plurality of spaced apart longitudinally extending slots to provide spaced blade portions, one of said blade portions being marked off 35 with scale divisions along its outer edge and having its inner edge notched with the points of the notches in alignment with the divisions of the scale.

4. A tri-square including a blade, a stock, 40 and adjustable gage arms carried by the stock and means for moving said gage arms toward and away from the outer edge of the stock.

5. A tri-square including a blade, an extensible stock having a main stock portion 45 and a supplemental stock portion slidably connected from movement toward and away from each other, and gage arms slidably carried one by the main stock portion and one by the supplemental stock portion for 50 movement toward and away from the outer edges of their respective stock portions.

6. A tri-square including a blade, an extensible stock having a main stock portion and a supplemental stock portion movable 55 toward and away from each other, both stock portions being provided with recesses and adjustable gage arms carried one by the main stock portion and one by the supplemental stock portion, said gage arms being 60 movable toward and away from the outer edges of their respective stocks and in retracted position seating flush in the recesses formed in said stocks.

7. A tri-square including a blade, a stock 65 cut-away at its ends to form seats and provided in its front and rear faces with transversely extending channels communicating with the seats, the ends of the stock being further slotted and provided with bores 70 passing through the slots, adjustable gage arms including U-shaped portions, the arms of which seat in the channels of the stock, the intermediate portions of said gage arms being provided with lateral extensions seating 75 in the seats of the stock, threaded studs carried by said extensions and projecting into the bores of the stock, and adjusting nuts positioned in the slots of the stock and through which the studs are threaded. 80

In testimony whereof I affix my signature in presence of two witnesses.
